(57) **CLAIM**

What is claimed is the new, original and ornamental design for a deodorizer or Similar Article, as shown in FIGS. 1 to 6.

DESCRIPTION

FIG. 1 is a front, top, left side perspective view of the Design for the deodorizer or similar article thereof.

FIG. 2 is an enlarged left side view of the Design for the deodorizer.

FIG. 3 is an enlarged top plan view of the Design for the deodorizer.

FIG. 4 is an enlarged front side view of the Design for the deodorizer.

FIG. 5 is an enlarged right side view of the Design for the deodorizer; and,

FIG. 6 is an enlarged rear side view of the Design for the deodorizer.

The broken line showing of environmental structure in FIGS. 1-6 is for illustrative purposes only and forms no part of the claimed design.
